UNITED STATES PATENT OFFICE

HAROLD J. STEAD, OF GENEVA, NEW YORK

SPRING-CONTROLLING DEVICE

Application filed July 30, 1928. Serial No. 296,184.

This invention relates to a new and improved spring controlling device for automotive and other vehicles and discloses an improvement over the structure disclosed by me in my co-pending application for spring checking device, Serial No. 219,077, filed September 12, 1927.

In constructing vehicles it is usual to interpose flexible springs between the axles carrying the wheels and the body of the vehicle so that when the wheels pass over an inequality in the road which will raise them abruptly upwardly the springs will be flexed so that the axle may approach the body without transmitting a direct shock to the body which would be the case if the axles were rigidly affixed to the body. When the spring has thus been flexed it will in turn return to its normal position thus raising the body upwardly. When movement of this character has been started the inertia of the parts concerned will cause a continuing flexing of the springs in diminishing distances until the original relation of parts has been again attained. The result of the movement thus transmitted to the body of the vehicle is a certain degree of discomfort to the occupants and the main object of my invention is to design a structure which will control to a certain degree the initial flexing of the springs when the wheels pass over an inequality in the road so that the axles will approach the body more slowly and to a less extent than if the flexing of the springs was not controlled.

Another object of my invention is to provide a device which will exert a lesser resistance to the flexing of the springs when the axle is moving upwardly under the first shock caused by its passing over an inequality in the road than will be exerted on the subsequent flexing of the spring so that the initial force exerted on the parts will be minimized.

Another object is to provide a device in which limited flexing of the springs will be

permitted without any control of such flexing being exercised by the device.

Another object is to provide an adjustable means whereby the amount which the flexing of the springs will be controlled may be varied at will.

Other objects and advantages relate to the size, shape and arrangement of parts all as will more fully appear from the following description taken in connection with the accompanying drawings in which:

Figure 1 is an elevation partly broken away and partly in section showing my device assembled on the frame and an axle of a vehicle.

Figure 2 is a section on line 2—2 of Figure 1.

Figure 3 is a section on line 3—3 of Figure 1.

Figure 4 is a section on line 4—4 of Figure 2.

Figure 5 is a perspective view of one of the brake shoes used with my device.

My device consists of a circular housing —1— having a closed end —2— and an open end —3—. Housing —1— has its inside face tapered so that its diameter at the open end —3— is greater than the diameter at the closed end —2—. Altho it is not essential I prefer to place in the lower end of housing —1— adjacent the vertical walls a circular lining —4— of an appropriate friction material.

A brake shoe —5— and a similar brake shoe —6— are positioned in housing —1— in contact with lining —4—. The two brake shoes —5— and —6—, as perhaps may best be seen from Figure 4, together make a complete circle so that in the normal position they are in contact with each other and their periphery is in contact throughout with lining —4—. Brake shoes —5— and —6— are similar in construction and may be interchangeably used so that a description of one is a description of the other. Brake shoe —5— is semi-circular in shape and is provided adjacent one end with a bearing surface

75

90

—7— which when brake shoes —5— and —6— are in position will be but a short distance from lining —4—. Another bearing surface —8— in the same plane with bearing surface —7— is positioned adjacent the axis of the circular brake shoe formed by the combination of brake shoes —5— and —6—. Similar bearing surfaces —7'— and —8'— are provided on brake shoe —6—. Bearing surfaces 7 and 7' are provided with vertical pins —9— for a purpose hereinafter to be described. The outside surfaces of brake shoes —5— and —6— are tapered so that when they are in position in housing —1— the outside surface of brake shoes —5— and —6— will be in parallel relation to the inside surface of housing —1—.

For the purpose of retaining brake shoes —5— and —6— within housing —1— and for the purpose of adjusting them in relation to housing —1— I provide a cover plate —10— having a central aperture —11— and being externally threaded on its inner end. The inner face of the open end —3— of housing —1— is internally threaded so that cover —10— may be threaded into housing —1—. Cover —10— is provided with a depending flange —12— on its inner face of a size and shape to register with the upper surfaces of brake shoes —5— and —6—. It will be understood that the distance which brake shoes —5— and —6— may be forced down into housing —1— will be controlled by cover 10, and it will also be understood that the farther brake shoes —5— and —6— are forced into housing —1— the greater will be the pressure of the brake shoes —5— and —6— against the lining —4—. Cover —10— is provided on its outside edge with a series of spaced notches —13—. A set screw —14— is positioned in the outer edge of housing —1— so that it may enter one of the notches —13— to hold cover —10— from rotation after it has been adjusted to the desired position.

A right angular crank arm —15— having an end —16— rectangular in cross section is placed through aperture —11— in cover —10— with the end —16— positioned between the brake shoes —5— and —6—. End —16— has on its top face a spring —17— with one end bent outwardly and in contact with bearing surface 8'. Another spring —18— extends outwardly from the upper surface of end —16— and is upwardly bent and in contact with bearing surface 7'. A bracket —19— is positioned on one end of member 16 immediately beneath spring 18. Springs 17 and 18 and bracket 19 are rigidly secured to end 16 by means of screw 20. Spring 18 and bracket 19 are provided with slots 21 and 22 for the reception of pin 9 to prevent any relative axial movement of brake shoe —6— and crank —15—.

End —16— is provided on its lower face with a spring —23— similar to spring 17 and

in contact with bearing surface 8. It is also provided with a spring —24— similar in shape and position to spring 18 and in contact with bearing surface 7. A bracket —25— similar to bracket 19 is positioned on the end of end 16, springs 23 and 24 and bracket 25 being rigidly affixed to end 16 by screw 26. Spring 24 and bracket 26 are provided with slots 27 and 28, respectively, to receive a pin 9' on brake shoe 5.

Housing —1— is provided with a plurality, in this case shown as three, of stud screws 29 extending outwardly from the closed end —2— of housing —1— by means of which housing —1— is rigidly secured to the frame 30 of a vehicle, not shown, in the position shown in Figure 1. The end of crank 15 opposite to the end 16 is provided with a ball, not shown, confined in a socket 31 on the end of a link 32. The opposite end of link 32 is provided with a ball, not shown, confined in a socket 33 on clamp 34 which is rigidly secured to an axle 35 of the vehicle so that when the axle 35 approaches the frame 30 the crank 15 will be moved upwardly and its end 16 will be rotated in housing —1—. Similarly when frame 30 moves upwardly away from axle —34— to and beyond their normal relation the crank 15 will be moved downwardly and its end 16 rotated in housing —1— in the opposite direction.

When the crank —15— is rotated thereby rotating end 16 in the direction indicated by an arrow on Figure 4 springs 17 and 23 will be depressed so that during the initial movement of end —16— there will be no effect on brake shoes —5— and —6— inasmuch as the frictional resistance between them and lining —4— is greater than the strength of springs 17 and 23. When, however, the end —16— has been rotated a sufficient distance so that the end of spring —17— is in contact with bearing surface 8' and with end 16 and spring 23 is in contact with bearing surface 8 and the opposite side of end 16, force will be exerted on brake shoes —5— and —6—, which force will tend to rotate brake shoes 5 and 6 in housing —1— and at the same time will tend to force brake shoes —5— and —6— outwardly and thus increase the friction between brake shoes —5— and —6— and lining —4—. Such frictional resistance between brake shoes —5— and —6— and lining —4— will resist the rotary movement of end 16 and will bring it to rest sooner than would be the case if its rotary movement was not resisted.

When the end 16 is rotated in the opposite direction springs 18 and 24 will be depressed until they contact with brackets 19 and 25, respectively, to prevent any further flexing of springs 18 and 24. The initial movement of end 16 during which springs 18 and 24 are depressed will not affect brake shoes 5 and 6 inasmuch as the friction between brake shoes

—5— and —6— and lining —4— is greater than can be overcome by springs 18 and 24. When spring 18 is in contact with bracket 19 and with bearing surface 7' at which time spring 24 is in contact with bracket 25 and bearing surface 7, the further rotary movement of end 16 will exert force against brake shoes 5 and 6, part of such force tending to rotate brake shoes —5— and —6— in housing —1— and part of such force tending to move brake shoes —5— and —6— outward and increase the friction between them and lining —4—. The resistance of brake shoes —5— and —6— to the further rotation of end 16 will cause end 16 to come to rest sooner than would be the case if such rotary movement were not resisted.

When the end 16 is rotated in the direction indicated by the arrow on Figure 4 the points against which it will apply force against brake shoes —5— and —6— are near the axis of housing 1 so that the direction of such force will be such that the major portion thereof will be expended in an effort to force brakes shoes —5— and —6— outwardly and into greater frictional contact with lining —4— and therefore a greater resistance will be offered to the further rotation of end 16 than will be the case when end 16 is rotated in the opposite direction. In the latter case the points where the force from the end 16 is applied to brake shoes 5 and 6 are adjacent the periphery of the circle formed by brake shoes 5 and 6 so that the major portion of force so exerted by end 16 will be expended in the direction of rotation of brake shoes —5— and —6— and the lesser portion will be expended in a direction tending to force brake shoes —5— and —6— outwardly and into greater frictional contact with lining —4—.

The advantage of applying the force of the rotating end 16 in different positions on brake shoes 5 and 6 depending upon the direction of rotation of end 16 lies in the fact that when springs are controlled by devices of this character the result to the body of the vehicle and the occupants thereof is better if a greater resistance is offered to the flexing of the springs 36 of the vehicle when they are moving in one direction than when they are moving in the other.

It will be obvious that the size of my device and the materials of which it is made may be varied to a considerable extent and it will also be obvious that the initial pressure between brake shoes —5— and —6— and housing —1— or lining 4, if such is used, may be varied to suit different conditions and sizes and weights of vehicles by the rotation of cover 10.

It will also be obvious that the points at which force from the rotating end 16 is applied to brake shoes —5— and —6— may be varied with relation to the axis of housing —1— depending upon the resistance which it

is desired to offer against the rotation of end 16.

It will also be apparent that although I have shown only one device in position on a vehicle that a plurality of such devices may be used, and usually are, so that the movement of all of the springs of a vehicle may be controlled. It will also be obvious that the length of crank 15 and link 32 may be varied to accommodate my device to different types of vehicles, for altho I have shown and described a specific structure and form of part as an exemplification of an embodiment of my invention I do not desire to restrict myself to the exact size, shape or relation of parts as various changes may be made within the scope of the appended claims.

I claim:

1. In a device of the class described, a circular housing, a circular member separable on a line at right angles to its axis disposed in the housing in frictional contact therewith, a crank rotatably mounted inside the circular member, means for yieldingly holding the crank out of contact with the circular member, means for rotating the crank, and means for holding the crank and circular member in fixed axial relation.

2. In a device of the class described, a housing, a circular member separable on a line at right angles to its axis disposed in the housing in frictional contact therewith, a crank rotatably mounted in the housing and having opposed faces adapted to contact with the circular member when the crank is rotated, the points of contact between the crank and the circular member when the crank is rotated in one direction being a greater distance from the axis of the circular member than the points of contact between such members when the crank is rotated in the opposite direction, and means for rotating the crank.

3. In a device of the class described, a housing, a circular member separable on a line at right angles to its axis disposed in the housing in frictional contact therewith, a crank rotatably mounted in the housing and having opposed faces adapted to contact with the circular member when the crank is rotated, the points of contact between the crank and the circular member when the crank is rotated in one direction being a greater distance from the axis of the circular member than the points of contact between such members when the crank is rotated in the opposite direction, means for holding the crank and circular member in fixed axial relation, and means for rotating the crank.

4. In a device of the class described, a housing, a circular member separable on a line at right angles to its axis disposed in the housing in frictional contact therewith, a crank rotatably mounted in the housing and having opposed faces adapted to contact with the circular member when the crank is

rotated, the points of contact between the crank and the circular member when the crank is rotated in one direction being a greater distance from the axis of the circular member than the points of contact between such members when the crank is rotated in the opposite direction; means for yieldingly holding the crank out of contact with the circular member, means for holding the crank and circular member in fixed axial relation, and means for rotating the crank.

In witness whereof I have hereunto set my hand this 18th day of May, 1928.

HAROLD J. STEAD.
